UNITED STATES PATENT OFFICE.

EDWIN FORBES, OF FLATBUSH, NEW YORK.

RUBBER OVERSHOE.

SPECIFICATION forming part of Letters Patent No. 378,245, dated February 21, 1883.

Application filed December 23, 1887. Serial No. 253,796. (No model.)

To all whom it may concern:

Be it known that I, EDWIN FORBES, of Flatbush, in the county of Kings and State of New York, have invented a new and useful Improvement in India-Rubber Overshoes, of which the following is a specification.

My invention relates to india-rubber overshoes which have formed in their uppers and extending from the edge of the foot-opening 10 lengthwise toward the toe flutes or corrugations, whereby the expansibility of the upper is increased without reference to the extensibility or stretching properties of the india-rubber. As heretofore made, the ends of the 15 flutes or corrugations which are presented at the edge of the foot-opening have been left open, and consequently have afforded channels through which snow and water might easily enter. To prevent the entrance of snow 20 and water into the channels formed by the flutes or corrugations, I form the shoe with such flutes or corrugations closed at the ends which are presented at the edge of the foot-opening; and in order to permanently retain 25 the flutes or corrugations in shape, so that the shoe will not soon become very loose upon the foot, I insert between the outer ply of india-rubber and the lining a key-piece or stiffener, which conforms in transverse section to the 30 shape of the flutes or corrugations, and is made of a material stiffer than that which forms such outer ply.

The invention will be hereinafter particularly described, and pointed out in the claims. 35 In the accompanying drawings, Figure 1 is a perspective view of an india-rubber shoe embodying my invention. Fig. 2 is a longitudinal section of the toe portion of the shoe, showing the toe of the boot as in place therein. 40 Fig. 3 is a transverse section of a portion of the upper, showing the flutes or corrugations and the key-piece or stiffener in place therein and upon a slightly larger scale than Figs. 1 and 2; and Fig. 4 is a perspective view of the 45 key-piece or stiffener in an inverted position.

Similar letters of reference designate corresponding parts in all the figures. 50 The shoe embodying my invention has formed in its upper portion flutes or corrugations *a*—that is to say, the material of which the shoe is made is fuller than would otherwise be necessary—and the surplus material is

gathered at the upper toe portion, so as to form the flutes or corrugations *a*, which extend from the edge *b* of the foot-opening lengthwise toward the toe. As the shoe is vulcanized with the flutes or corrugations in proper form, its normal condition will be with the material gathered in these flutes or corrugations, and therefore the shoe will have an expansibility independent of the extensibility or stretch of the material of which it is formed, and will fit easily upon the foot, and will not bind tightly upon the instep, as rubbers are so apt to do, especially in case the foot be slightly 65 swollen.

To aid in maintaining the flutes or corrugations in their normal condition, and also to give the shoe a greater strength to resist stretch or expansibility than it would have if the 70 flutes or corrugations were not re-enforced in any way, I provide a key-piece or stiffener, *B*, which is shown best in Figs. 3 and 4. This key-piece or stiffener *B* is also fluted or corrugated and conforms in transverse section to 75 the shape of the flutes or corrugations *a*, and the key-piece *B* is introduced between the outer ply, *s*, of india-rubber and the lining *s'*, and may be cemented or otherwise secured to these fabrics. The end of the key-piece or 80 stiffener, which is presented at the front edge, *b*, of the foot-opening, is closed, as shown at *b'*, and therefore serves to close these ends of the flutes or corrugations *a* and prevent snow and water from entering the channels which 85 they form. Inasmuch as these ends of the flutes or corrugations are closed, I gain all necessary expansibility in the shoe without employing open-ended flutes or corrugations, which form channels through which the snow 90 and water may pass downward into the shoe.

The key-piece or stiffener *B* may be of india-rubber and should be stiffer or harder than the material of which the outer ply, *s*, of the shoe is formed. This key-piece will give the 95 flutes or corrugations sufficient stiffness and contractile tendency, so that they will at all times maintain the shoe with a snug fit upon the boot, and will at the same time be sufficiently elastic or yielding to prevent the shoe 100 binding unpleasantly on the foot.

What I claim as my invention, and desire to secure by Letters Patent, is—

1. The india-rubber shoe herein described,

having in its upper portion flutes or corrugations extending longitudinally from the edge of the foot-opening toward the toe, the ends of the flutes or corrugations which are at the edge of the foot-opening being closed to prevent the entrance of snow and water, substantially as herein described.

2. The india-rubber shoe herein described, having its material gathered in flutes or corrugations *a*, and having a key-piece, *B*, of ma-

terial stiffer than the shoe upper, introduced between the upper and its lining, and conforming in transverse section to the shape of the flutes or corrugations, and serving to maintain the flutes or corrugations in shape, substantially as herein described.

EDWIN FORBES.
